UNITED STATES PATENT OFFICE.

CHARLES JOSHUA LANE, OF LONDON, ENGLAND, ASSIGNOR TO CYRIL FRANK ELWELL,
OF LONDON, ENGLAND.

SEPARATING OR SORTING APPARATUS.

1,422,807.

Specification of Letters Patent.

Patented July 11, 1922.

Application filed October 1, 1921. Serial No. 504,812.

To all whom it may concern:

Be it known that I, CHARLES JOSHUA LANE, a subject of the King of England, residing at Tottenham, London, England, have 5 invented certain new and useful Improvements in Separating or Sorting Apparatus, of which the following is a specification.

This invention is for improvements in or relating to separating, sorting, or sifting apparatus and the like, and has for its object 10 to provide an improved construction of the same.

The apparatus hereinafter described is particularly adapted for use in connection 15 with a method of coating metallic articles with a protective covering, like galvanizing, the process consisting in tumbling the articles in contact with a granular or comminuted material which forms the protective 20 coating. The articles and the fine material are treated in a rotatable drum, and the apparatus hereinafter described is used to separate the articles from the excess material and to return the fine material to a hopper 25 or storage receptacle wherefrom it can be drawn as required. It will be understood, however, that the apparatus herein-after-described may be put to other uses than the aforesaid, being used for sorting 30 or sifting any mixture of materials which have to be so treated.

According to this invention there is provided in sifting or sorting apparatus the combination of a stand provided with bearings 35 to receive a drum containing the material to be sifted, said bearings supporting the drum so that its lower surface has a slight downward inclination from the horizontal, an open-ended rotatable sieve which 40 has its axis below and parallel with the drum axis and which is of conical shape so that its lower surface has a slight downward inclination from the horizontal in the opposite direction to that of the drum aforesaid, and means for collecting the material 45 separated by said sieve. The means for collecting the separated materials may, for example, comprise a guide or chute to direct material from the drum to the sieve, and a 50 separate guide receiving material from the inside of the sieve and delivering it to any required point. Such means further comprise a guide to collect the material which

passes through the sieve and to deliver it, for example, by means of a screw conveyor 55 to any convenient outlet.

The reason for arranging the bearings of the drum in the manner above-described, is that by slow rotation of the drum, an automatic delivery of the contents therefrom 60 can be ensured by means of the downward slope of the bottom of the drum.

Other features of the invention relate to certain details of construction as herein-after-described and illustrated.

In the accompanying drawings which 65 illustrate a particular embodiment of this invention—

Figure 1 is a side elevation of the sieve and its associated parts,

Figure 2 is an end elevation looking from the left-hand side of Figure 1,

Figure 3 shows an end view of the apparatus in Figure 1 (looking from the right-hand side), in combination with a conveyor 75 and hopper for the storage of the powder,

Figure 4 is a perspective view of a detail of Figure 1, and

Figure 5 shows the construction to a larger scale of a detail of Figure 3.

Like reference characters indicate like parts throughout the drawings.

Referring first to Figures 1 and 2, the apparatus comprises a stand 10 built up of suitable material such as angle-iron, and 85 this stand is provided at the top with bearings to receive a rotatable drum, indicated in chain lines at 11, which contains the material to be sorted or sifted.

Conveniently this drum comprises a cylindrical portion with end plates 12 closing that portion, and a shaft 13 secured to said end-plate. In order to provide for the removal of the material from the interior of the drum 11, the end-plate is removed at 95 one end, (the right-hand end in Figure 1), and that end of the drum is supported upon rollers 14. The other end of the drum is supported in a bearing indicated generally by the reference character 15 in Figure 1, 100 and the detailed construction of this bearing is illustrated in Figure 4. It comprises a semi-cylindrical part 16, which is provided along one side with an upstanding wall 17. At one end of the part 16 there is 105 provided a complete cylindrical bearing 18,

these parts being preferably all formed integrally with one another. This bearing is mounted on the framework 10 (preferably being made integral with the part 28 hereinafter mentioned) so that it is open on its upper side and its shaping facilitates the insertion of the shaft 13 into it. The drum 11 is brought into position over the bearing and is guided down into the bearing by the wall 17. A bolt 19 or other convenient construction of peg is inserted through the wall 17 or any other convenient part of the bearing to engage a suitable circumferential recess in the shaft 13 for the purpose hereinafter set forth.

Means are provided for imparting a slow rotation to the drum 11, such means conveniently comprising fast and loose belt-pulleys 20, 21 mounted on a shaft 22 which carries a worm and drives a worm-wheel situated in the casing 23. This worm-wheel is mounted on a suitable shaft which is coaxial with the bearing 15 and lies within the cylindrical part 18 thereof. This shaft is provided with a diametral slot at the end which lies in the bearing 18, and a dog situated within this slot is adapted to be projected therefrom by means of a suitable push-rod 24, see Figure 1, extending out from the other end of the shaft. A hand-wheel 25 which is rotatable on the shaft 24 but is restrained from axial movement thereon, provides a convenient means for moving the dog aforesaid whilst the shaft is in rotation, this movement of the dog putting it either into engagement with a diametral slot on the end of the shaft 13 to effect a driving engagement therewith or withdrawing it to release the shaft 13.

The bearings 14, 15 are so disposed that the drum 11 when mounted in them has a slight downward inclination towards the right-hand end in Figure 1, and the end plate at this lower end is removed after the drum has been inserted in place. A housing 26 having a removable cover 27 encloses this end of the drum, and also provides a support for a beam 28 which is provided to support the end-plate after it has been detached from the drum ready for lifting it away. The slow rotation aforesaid which is imparted to the drum 11, together with its downward inclination causes any material in it to be delivered slowly from the open end into the housing 26 and this material passes downwards through a chute 29.

A rotatable sieve is mounted in the frame 10 in a convenient position below the drum 11. This sieve is supported at one end in a bearing 30 and at the other end on rollers 31, and these are so disposed that the axis of the sieve is parallel with the axis of the drum 11 aforesaid, that is to say it has a slight downward inclination from the horizontal towards the right in Figure 1. The

reason for making the two axes parallel is to enable a chain drive to be used for the various parts as hereinafter-described.

The sieve is constructed of any suitable frame-work covered by netting or gauze 32 of a mesh appropriate to the materials which are to be separated. Preferably the sieve is of octagonal or other angular cross-section, and it is tapered or coned with the small end towards the right, this end encircling the open end of the delivery chute 29 aforesaid so that material passing therethrough is delivered into the sieve. The angle of conicity of the sieve is so selected that its lower edge 33 is sloped downwards in the opposite direction to the slope of the drum 11, that is to say downwards towards the left in Figure 1, and the material in the sieve which does not pass through the gauze 32 is thereby caused to travel through the sieve from right to left in Figure 1. The right-hand end of the sieve is open and projects into a delivery chute 34, the upper part of the end of this chute being cut away at 35 to receive the end of the sieve. A curtain or flap 36 of canvas or any other suitable material is provided in the chute 34 to prevent the escape of dust and the like therethrough, but this flap does not interfere with the passage of the heavier articles which are retained by the sieve in its sifting operation, and these heavier or larger parts are delivered through the chute 34 as hereinafter described.

A grating 37 is provided under the smaller open end of the sieve as a trap to receive any material which passing from the chute 29 into the open end of the sieve is discharged from that end for any reason. This grating effects a partial separation or sifting of the material by allowing the finer portions to fall therethrough, and the material retained on the grating is removed periodically through a door 38 on the end of the frame 10.

Below the sieve aforesaid there is mounted a screw conveyor indicated generally by the reference 39. This conveyor is mounted with its axis parallel to the axis of the sieve and the drum 11 and is arranged in a trough 40. All the material passing through the sieve is directed downwards into this trough and is there transported by the conveyor to an outlet 41 at the end thereof, or at any other convenient place.

As above-stated the axes of the drum 11, sieve and conveyor are all parallel with one another and the necessary drive is imparted to each of them by a chain 42. This chain receives its drive from a sprocket wheel 43 mounted on the shaft of the worm-wheel aforesaid in the casing 23 and it engages similar sprocket-wheels 44, 45 mounted on the shaft of the conveyor and of the sieve respectively. It also passes over a jockey-pulley 46 which is provided with any con-

venient means of adjustment for taking up any slack in the chain. This jockey-pulley is preferably arranged in the position shown in Figure 2 in order to provide a suitably long arc of contact of the chain 42 with the wheel 45 which drives the sieve. A suitable guard 47 is provided to cover the exposed gearing of the machine.

The axes of the various rotating parts hereinbefore mentioned are all parallel with one another and sloped downwards on the horizontal, and in order to prevent endwise movement of these parts resulting from this sloping, any suitable means may be provided. In the case of the drum 11 this restraint is effected by the peg 19 engaging a groove in the shaft 13. In the case of the sieve and the conveyor collars 48 may be provided to engage the ends of the bearings to effect the necessary restraint.

The frame 10 is preferably provided with a sheet metal cover so that the whole of the apparatus is entirely enclosed, and in order to provide for convenient access to the conveyor 39, or for its withdrawal when required, the portion 49 of the end of this covering, as shown in Figure 3, is made readily detachable.

In the preferred arrangement the apparatus illustrated in Figures 1 and 2 is used, as shown in Figure 3, in combination with a hopper or storage bin to receive the material which passes through the sieve. On the outlet 41 from the conveyor there is provided a chute 50 to direct the material issuing therefrom into a conveying device 51, which may take any desired form, but is illustrated as an elevator. This conveying device delivers the material to a hopper 52 wherein the material is stored until required.

Another feature of this invention relates to the construction and arrangement of the discharge outlet from this hopper 52, the improvement consisting in making this outlet adjustable so that material can be delivered at different points.

This construction is illustrated in Figure 3 and certain details are also illustrated on a larger scale in Figure 5. The hopper 52 terminates at its lower end in a cylindrical tube-like member 53. Surrounding this tube and coaxial with it there is an internally screw-threaded socket 54 which is secured on the lower end of the hopper 52 by welding as at 55 or in any other convenient manner. The internal diameter of the socket 54 is sufficiently larger than the external diameter of the tube 53 to permit the entry into it of a pipe-nipple 56 which is screwed in the usual way at the ends 57, 58. The portion 57 screws into the socket 54 and encircles the tube 53, and any desired lengths of the threads are engaged, but the nipple 56 is not screwed home, being left free to ro-

tate through any desired angle not more than one complete revolution. The part 58 of the nipple is screwed into the stem of an inverted T-piece 59, and a tube 60 of any desired length is screwed into one of the arms of this T-piece. The other arm of the T-piece is closed by a plug 61. The tube 60 thus provides a swivelling outlet-pipe from the hopper which is constructed entirely of the standard pipe-connections 54, 56, 59, and any material delivered from the hopper can pass into the tube 60 without any possibility of fouling the rubbing surfaces of the swivel joint, these rubbing surfaces being constituted by the screw-threads on the parts 54 and 57. In the construction shown, the tubes 60 is arranged horizontally, although it will be appreciated that it may be inclined downwards, if so desired, and when it is used horizontally the outlet from the tube is constituted by the downwardly-directed stem 61 of a T-piece 62 secured on the end of the tube. Preferably also a screw-conveyor is mounted in the tube 60 to convey the material from the inlet end below the tube 53 on the hopper to the outlet end. This conveyor is preferably operated through a worm-gear by an electric motor 63 mounted on a suitable bracket secured to that end of the T-piece 59 which is closed by the plug 61. It will be seen that the weight of the bracket, motor and gearing balances wholly or in part the weight of the tube 60 and its contents.

Preferably a handle 64 is provided on the delivery end of the tube 60 to enable it to be rotated, and this handle may be provided with an adjustable grip 65 which controls the switch for the motor 63 so that when the operator grips the handle 64 to bring the tube 60 into the desired position, he can simultaneously start up the motor 63 and thereby set the screw-threaded conveyor in motion so that the material is ready to be delivered from the outlet 61 as soon as it has been brought to the desired position.

As above-stated, this apparatus is particularly adapted for use in a process of covering articles with a protective coating applied in the form of a powder, the process being carried out in the drum 11, which is then mounted in the stand 10 in the manner hereinafter described to enable the powder to be separated from the articles. The coated articles are delivered through the chute 34 from the interior of the sieve and the other material is finally delivered into the hopper 52 ready to be distributed for use again, but it will be appreciated that the apparatus may also be used for sifting or sorting any other desired materials.

What I claim as my invention and desire to secure by Letters Patent is:—

1. In sifting apparatus, the combination of a stand, a drum open at one end ro-

4
 tatably and removably mounted in said stand with its lower surface inclined downwardly from the horizontal, and its open end lower than its closed end, a housing 5 rounding the open end of said drum, a chute leading downwards from said housing, an open-ended conical sieve rotatably mounted in said stand with its axis below and parallel with the axis of said drum, the angle 10 at the apex of the cone of said sieve being greater than twice the angle of inclination of the drum axis downwards from the horizontal, said sieve being arranged with its smaller open end enclosing the lower end 15 of said chute, a delivery chute disposed below the open larger end of said sieve, and a tray extending lengthwise of said sieve below it to receive material passing through it.

2. In sifting apparatus, the combination 20 of a stand, a bearing formed with a semi-cylindrical lower portion, a plain vertical extension at one side of said lower portion, a drum closed at one end, a trunnion centrally secured on said closed end engaging 25 said bearing, bearing rollers on the frame supporting the other open end of said drum, said bearings being so disposed that the drum slopes downwardly from the horizontal towards its open end, a housing 30 rounding the open end of said drum, a chute leading downwards from said housing, an open ended conical sieve rotatably mounted in said standard with its smaller end sur-

rounding the lower end of said chute, means for collecting material passing through the 35 conical wall of the sieve, and means for collecting material discharged from the other open end of the sieve.

3. In sifting apparatus, the combination of a stand, an open-ended drum rotatably 40 mounted in said stand, and sloped downwardly from the horizontal with its open end lower than its closed end, a conical sieve open at both ends, mounted in said stand below said drum with its axis parallel 45 with that of said drum, a housing surrounding the open end of said drum, a chute extending downwards from said housing and projecting into the smaller end of said conical sieve, a trough on said stand extending 50 below said sieve to receive material therefrom, a feed screw mounted adjacent said trough, an outlet from said trough, a conveyor receiving material from said outlet, a hopper receiving material from said conveyor, a smooth outlet tube at the lower end 55 of said hopper, an internally-screw-threaded socket secured on said hopper surrounding said outlet tube, an externally-screw-threaded nipple also encircling said outlet and 60 screwed into said socket, engaging it by a portion of its screw-threaded length, a tubular member secured on said nipple to turn with it in said socket, and a screw conveyor mounted in said tubular member.

CHARLES JOSHUA LANE.
